(57) **CLAIM**

The ornamental design for a strain relief for a cable connector, as shown and described.

DESCRIPTION

FIG. 1 is a top perspective view of a strain relief for a cable connector showing our new design;

FIG. 2 is top view thereof;

FIG. 3 is a left side view thereof;

FIG. 4 is a right side view thereof;

FIG. 5 is a bottom view thereof;

FIG. 6 is front view thereof;

FIG. 7 is a rear view thereof; and,

FIG. 8 is a rear view thereof without the cable connector in broken lines.

Broken lines are used to show a cable connector and a cable, both of which form no part of the claimed design.
